UNITED STATES PATENT OFFICE.

MATTHEW HENRY WHITTAKER, OF MANCHESTER, ENGLAND, ASSIGNOR TO LINOTYPE AND MACHINERY LIMITED, OF LONDON, ENGLAND.

MATRIX FOR USE IN THE PRODUCTION OF TYPE-BARS.

1,098,867.

Specification of Letters Patent.

Patented June 2, 1914.

Original application filed July 17, 1912, Serial No. 709,902. Divided and this application filed September 27, 1913. Serial No. 792,079.

To all whom it may concern:

Be it known that I, MATTHEW HENRY WHITTAKER, a subject of the King of the United Kingdom of Great Britain and Ireland, residing at Norton House, Hornby Road, Old Trafford, Manchester, in the county of Lancaster, England, have invented new and useful Improvements in Matrices for Use in the Production of Type-Bars, of which the following is a specification.

This invention relates to matrices for use in the production of type bars and particularly those type bars which, when in operative form and ready for use, are, in addition to printing surfaces of type height, provided with upstanding spurs or projections of greater than type height. Type bars of that description are fully described and claimed in an application for Letters Patent Serial Number 709,902, filed July 17th 1912, hereinafter referred to as the original application, from which original application the present one has been divided.

The invention will be best understood by reference to the accompanying drawings, in which:—

Figure 1 is a perspective view of one of the improved matrices adapted to cast a section of a single rule; Fig. 2 is a vertical section of a portion of the same; Fig. 3 is a perspective view of portions of two juxtaposed type bars with a single rule such as would be cast from the matrix shown in Figs. 1 and 2; Fig. 4 is an end elevation of a series of juxtaposed type bars such as those shown in Fig. 3; Fig. 5 is a view similar to Fig. 1 of one of the improved matrices adapted to cast a section of a double rule, and Fig. 6 is an elevation of a part of a type bar with a double rule cast thereon as from the matrix shown in Fig. 5.

For the production of the before particularized type bars, the formative cavities 1 of the matrices 2, are provided with terminal depressions 3, see particularly Fig. 2, so as to produce on the resultant type bars 4 short and preferably tapered, spurs or projections 5, which, as shown in Fig. 3, project above type height, these spurs being situated either one at each end of the respective rule sec-

tion, as shown in the drawings, or at one end only of the said rule section.

When a series of the just described type bars 4 are imposed in the form, with adjacent rule sections in substantial alinement, 55 as indicated for example in Fig. 3, with the spurs 5 extending above type height (which latter is exemplified by the dimension *a* in Fig. 4) the said spurs can either be bur- nished down to type height, to bridge over 60 gaps existing between the rule sections of ad- jacent type bars, or left standing above type height for the purpose of perforating the sheets for the printing of which the type bars may be subsequently employed, all as 65 fully explained in the aforesaid original ap- plication.

For the production of type bars having double rule sections thereon, as shown in Fig. 6, the matrices, as shown in Fig. 5, 70 would have two side-by-side formative cavities 1, each like that previously described, and each producing a rule section of type height having upstanding spurs at its re- spectively opposite ends. 75

Having described my invention, I declare that what I claim and desire to secure by Letters Patent is:—

1. In a matrix for the production of type bars, a formative cavity adapted to produce 80 in combination a type-high printing surface and a spur of greater than type height at the end of said printing surface and adapted to be bent over to form a continua- tion thereof. 85

2. In a matrix for the production of type bars, a formative cavity adapted to produce in combination a type-high printing surface and a plurality of spurs of greater than type height, two of these spurs being situated at 90 respectively opposite ends of the type-high printing surface and adapted to be bent over to form a continuation thereof.

In witness whereof I have hereunto set my hand in the presence of two witnesses. 95

MATTHEW HENRY WHITTAKER.
